(57) **CLAIM**

I claim the ornamental design for a cat toy fort, as shown and described.

DESCRIPTION

FIG. 1 is a perspective view of a cat toy fort, showing my new design;

FIG. 2 is a front elevational view thereof;

FIG. 3 is a right-side elevational view thereof;

FIG. 4 is a rear elevational view thereof, the left-side elevational view being a mirror image thereof;

FIG. 5 is a top plan view thereof;

FIG. 6 is a bottom plan view thereof;

FIG. 7 is a bottom perspective view of the spinner mechanism inside FIGS. 1-6;

FIG. 8 is a right-side elevational view of FIG. 7;

FIG. 9 is a left-side elevational view of FIG. 7;

FIG. 10 is a front elevational view of FIG. 7, the rear elevational view being a mirror image thereof;

FIG. 11 is a top plan view of FIG. 7; and,

FIG. 12 is a bottom plan view of FIG. 7.

The broken lines depict environmental subject matter and form no part of the claimed design.
